UNITED STATES PATENT OFFICE.

CHARLES A. RICHARDS, OF CHICAGO, ILLINOIS, AND MABEL M. RIESTER, OF BUFFALO, NEW YORK.

MULTICOLOR-PRINTING PRESS.

1,417,569.

Specification of Letters Patent. Patented May 30, 1922.

Application filed September 4, 1917. Serial No. 189,440.

To all whom it may concern:

Be it known that we, CHARLES A. RICHARDS and MABEL M. RIESTER, citizens of the United States, respectively residing at Chicago, in the county of Cook and State of Illinois, and at Buffalo, in the county of Erie and State of New York, have invented certain new and useful Improvements in Multicolor-Printing Presses, of which the following is a specification.

This invention relates to multi-color printing presses.

It will be explained as applied to a press of the flat platen type although it may be applied to presses of other types.

Printing presses embodying the invention are particularly useful in the production of sheets on which numbers of vari-colored and shaded impressions appear, such for example as the color cards, inserts, folders, etc.; of manufacturers and dealers in paints and stains; colored goods of various kinds, and the like.

Heretofore it has been the usual practice to produce such sheets by preparing separate, different colored and shaded pieces which are subsequently pasted or otherwise secured to the sheets or to pass the sheets through the press once for each different color and shade. Attempts have been made to successfully print numbers of different colors and shade simultaneously at one impression, but such attempts have proven commercially unsuccessful due to the fact that, in a relatively short time, the colors become mixed and blended and a uniform grade of work is impossible.

One of the objects of this invention is to provide an improved multi-color printing press.

Another object is to provide a printing press wherein a large number of different colors and shades can be printed at one impression without danger of confusion and blending.

Another object is to provide a press wherein a plurality of colors may be accurately applied to a sheet at one impression.

Another object is to provide a multi-color

press having reliable and efficient ink distribution and application.

Another object is to provide a multi-color press wherein the number of different color impressions may be readily varied within the capacity of a particular installation.

Another object is to provide a multi-color press wherein the arrangement of colors may be readily changed to meet the varying demands of service.

Other objects and advantages will hereinafter appear.

An embodiment of the invention as applied to a flat platen press is illustrated in the accompanying drawings.

According to this invention the press has a plurality of sets of ink fountains, each individual fountain being adapted to hold ink of a different color or shade. The printing forms, which produce the desired impressions, are arranged in corresponding sets. Between each set of fountains and forms, and individual thereto throughout, is an ink distributing system, comprising rollers which transfer the colored inks from the fountains to the forms. One group of rollers of the ink distributing systems is selectively caused to contact with the sets of forms to selectively transfer the vari-colored inks thereto.

In the accompanying drawings:—

Fig. 1 is a side elevation of part of a press with the multicolor attachment applied thereto.

Fig. 2 is a front elevation of the same with the platen of the press removed and the chase in position and showing the inker rolls in elevated position.

Fig. 3 is an enlarged side elevation of the attachment with parts broken away and parts in section.

Fig. 4 is a top plan view of a corner portion of the attachment with parts broken away.

Fig. 5 is a detailed view of mechanism for driving the front rolls of the attachment and including a shoe device for holding a chain in proper contact with sprocket wheels carried by the shafts of the front rolls.

Fig. 6 is a rear elevation of a corner por-

tion of the attachment with parts removed and parts broken away.

Fig. 7 is a detailed longitudinal sectional view of a vibrator roll used in the attachment.

Fig. 8 is a side elevation of part of the roll frame of the attachment.

Fig. 9 is a side elevation of part of the ductor roll frame of the attachment.

10 Fig. 10 is a side elevation of part of the fountain supporting frame of the attachment.

Fig. 11 is a detailed perspective view of a section of one of the follower tracks used 15 in conjunction with the attachment.

Fig. 12 is a detailed perspective view of one of the roll bridges used in conjunction with the attachment.

Fig. 13 is a front elevation of one of the 20 follow tracks used upon the attachment.

Fig. 14 is an edge elevation of the track shown in Fig. 13.

Fig. 15 is a detailed vertical sectional view of the attachment taken on the line 25 15—15 of Fig. 3.

Fig. 16 is a similar view taken on the line 16—16 of Fig. 3.

Fig. 17 is a similar view taken on the line 17—17 of Fig. 3.

30 Fig. 18 is a similar view taken on the line 18—18 of Fig. 3.

Fig. 19 is a similar view taken on the line 19—19 of Fig. 3.

Fig. 20 is a similar view taken on the line 35 20—20 of Fig. 3.

In all the views the same reference characters are used to indicate similar parts.

Part of the frame of the press is shown at 1 in Fig. 1 of the drawings and the said 40 frame is provided at its forward portion with guides 2 which serve as means for guiding the form roller carriage 3 along the frame 1 in the usual manner. The carriage 3 is moved by arms 4 which are operatively connected with the said carriage by means of links 5. The arms 4 and their attachments are operated in the usual manner. A bull gear wheel 6 is journaled for rotation at the side of the frame 1 and is provided 45 at its side with an eccentric 7. A platen 8 is movably mounted upon the frame 1 of the press and arms 9 are pivotally connected with the said platen and pivotally connected with the bull gear wheel 6 at a point to one 50 side of the axis of the said wheel. The wheel 6 is rotated in any usual manner consequently the arms 9 are moved longitudinally and the platen 8 is moved toward and away from the chase 10 (see Figure 2) which 55 is supported in the usual manner upon the frame 1 of the press.

60 A fountain frame 11 is mounted upon the frame 1 and supports brackets 12 which extend from side to side of the said frame (as 65 most clearly shown in Fig. 15 of the draw-

ing.) The said brackets are arranged one above the other and spaced from each other and each bracket supports a series or set of fountains 13. The fountains on each bracket form a transverse set or row and are spaced 70 from each other so that the said fountains on the several brackets are arranged in vertical or longitudinal rows or sets (as shown in Fig. 15). Each fountain 13 is provided at its bottom with an inclined plate 14 which is secured at its upper edge portion and free at its lower edge portion as most clearly indicated at the intermediate portion of Fig.

3. Screws 15 are threaded in the bottom portions of the fountains 13 and bear at their 80 ends against the under sides of the plate 14 and may be used for varying the angle of inclination of the plates 14. Bearings 16 are provided at the sides of the frame 11 and shafts 17 are journaled in the said bearings. 85

The shafts 17 correspond in number with the brackets 12 and the said shafts are disposed opposite the said brackets and the fountains 13 carried thereby. Fountain rollers or sections 18 are mounted upon the 90 shafts 17 and enter the adjacent portions of the fountains 13 and form side walls for the said fountains. There is a fountain roller section 18 for each fountain 13 and all of the roller sections upon the same shaft 17 constitutes what is hereinafter referred to as a fountain roller set. The screws 15 force the lower free edges of the plates 14 into close engagement with the roller sections 18. Each individual fountain 13 is intended to 100

contain an ink of distinctive color or shade and inasmuch as the roller sections 18 form sides of the said fountains this ink adheres to the peripheries of the corresponding roller sections and is withdrawn from the fountains as the fountain rollers are rotated as hereinafter described. Handles 19 are fixed to the ends of the shafts 17 and may be used when it is desired to rotate the said shaft 105

manually for the purpose of spreading the 110 ink upon the peripheries of the roller sections 18 and for tritivating or working the ink between the edges of the plates 14 and the peripheries of the said roller sections. Ratchet wheels 20 are fixed to the shafts 17 115 and arms 21 are loosely mounted upon the said shafts. Pawls 22 are pivotally mounted upon the arms 21 and are provided with weighted end portions 23 which serve, by effect of gravity, to hold the pawls 22 in engagement with the teeth of the ratchet wheels 20. All of the arms 21 are pivotally connected with a bar 24 which extends transversely across the shafts 17. The bar 24 is pivotally connected at its lower end with an 120 arm 25 mounted upon a sleeve 26. The sleeve 26 is mounted upon a cross bar or shaft 27, best shown in Fig. 6 of the drawing. An arm 28 is fixed to the sleeve 26 and carries at its lower end a wheel 29 125

130

which travels upon the periphery of the cam 7 hereinbefore referred to. It is apparent that when the cam 7 rotates and the wheel 29 travels along the periphery thereof the 5 arm 28 is caused to rock back and forth about cross bar 27 and the bar 24 will rise and fall. The arm 28 carries with it the sleeve 26, the arm 25 moves with the sleeve and the bar 24 is reciprocated vertically. 10 During the upward movement of the bar 24 the pawls 22 escape, or move idly along the teeth of the ratchet wheels 20, but as soon as the bar 24 begins to move in a downward direction the pawls 22 engage the teeth of 15 the ratchet wheels 20 and upon further downward movement of the said bar 24 the ratchet wheels 20 are partially rotated and carry around with them the shafts 17. Therefore it will be seen that mechanical 20 means is provided for imparting step by step rotary movement to the fountain roller sections 18 mounted upon the said shafts 17. A roll frame 30 is located at the upper ends of the guides 2 and is connected with 25 the frame 11 by means of cross bars 31. A rod 32 extends across the upper portion of the frame 30. Links 33 are pivotally mounted at their upper ends upon the end portions of the rod 32 and a ductor frame 34 30 is pivotally connected with the lower ends of the links 33. Arms 35 are connected at their upper ends with the lower portion of the ductor frame 34 and the cross rod 27 passes through the lower portions of the 35 arms 35. The arm 35 at one side of the press is provided with spaced lugs 36 to receive between them a portion of the arm 25 as most clearly shown in Fig. 3 of the drawing. A screw 37 passes through one of the 40 lugs 36 and bears at one end against the end portion of the arm 25 which is located between the said lugs 36 and serves as means for adjusting the arm 25 with relation to the arm 35 to regulate the throw of arm 35 45 and consequently the movement of the ductor frame. The sides of the ductor frame 34 are vertically slotted as at 38 and blocks 39 are received in the said slots. Screws 40 pass through plates 41 mounted at the upper 50 ends of the slots 38 and the said screws bear at their lower ends against the upper ends of the uppermost blocks 39 and serve to hold the blocks in position in the slots 38 at the sides of the said ductor frame 34. Each of 55 the blocks 39 is provided with an elongated opening 42, the long dimensions of the said openings being vertically disposed. Bearings 43 are located in the openings 42 and screws 44 engage the opposite sides of the 60 said bearings and also engage the end portions of the blocks, 39. Therefore it will be seen that by adjusting the screws 44 the bearings 43 may be shifted along the openings 42 in the blocks 39. Shafts 45 are 65 loosely journaled in the bearings 43 and each carries a set of ductor roller sections 46 which correspond in number with the corresponding set of fountain roller sections 18. Each of the fountain roller sections 18 has its counterpart or corresponding roller 70 section in one of the ductor roller sections 46 and when the ductor frame 34 is moved towards the fountain rollers by the action of the arms 35, as hereinbefore described, each set of the ductor roller sections 46 encounters the periphery of its corresponding set of fountain roller section 18. Therefore as the fountain roller sets have been turned slightly during the rise of the ductor frame, a freshly inked surface is presented by each 75 individual fountain roller to the corresponding ductor roller section. 80

The rod 32, hereinbefore referred to, is pivoted in the upper portion of the frame 30 and the upper ends of the links 33 are fixed to the said rod 32. As shown, in Fig. 6 of the drawing, a spring 47 is connected at one end with the upper portion of the frame 30 and the other end of the said spring is connected with a collar 48 mounted upon 90 the rod 32. The spring 47 is coiled about the rod 32 between the collar 48 and the point of connection with the frame 30. The said spring, 47, is under tension with a tendency to counteract the weight of the 95 ductor frame 34 and its attachments carried at the lower ends of the links 33. Therefore the parts are balanced or substantially balanced upon the rod 32 and excessive lifting force is not required to move the ductor 100 frame 34 to carry the ductor rollers into engagement with the peripheries of the fountain rollers. By providing the adjusting screws 44 for the bearings 43 the shafts 45 of the ductor roller sections 46 may be positioned at proper distances apart in order to properly engage the peripheries of their respective and corresponding fountain roller sections 18. 105

The sides of the frame 30 are slotted as at 110 49 (Fig. 8) and blocks 50 are arranged in the said slots as most clearly shown in Fig. 3 of the drawing. Shafts 51 are fixed at their ends in the blocks 50 and the said shafts 51 are provided at points between their ends 115 with spiral grooves 52 as shown in Fig. 7. Sleeves 53 are rotatably mounted upon the shafts 51 and carry pins 54 having journaled friction rollers 55 which enter the grooves 52. Each of the sleeves 53 is surrounded by 120 a coating 56 of any suitable composition usually employed for forming inking rolls. The coatings 56 are provided with peripheral depressions 57 which divide the said coatings into sections corresponding in number with the sections 46 of the ductor rollers and the sections 18 of the fountain rollers. The sleeves 53, and the parts mounted thereon, constitute what are hereinafter referred 125 to as the vibrator rollers. When the ductor 130

frame 34 is in its lowermost position, as shown in Fig. 3 of the drawings, the peripheries of the ductor rollers encounter the peripheries of the vibrator rollers and inasmuch as the sleeves 53 and the coatings thereon of the said vibrator rollers are maintained in a continuous state of rotation, the roll sections 46 of the ductor rolls are rotated. The means for vibrating the sleeves 53 and the coating thereon will be explained hereinafter. As the sleeves 53 rotate, the rollers 55 moving along the spiral grooves 52 cause the said sleeves 53 to move longitudinally along the shafts 51 and axially 10 shift the rollers 56, and hence these rollers are termed the vibrator rollers. The ink, which the ductor roller sections receive from the fountain roller sections 18, is transmitted to the vibrator roller sections when the said 15 ductor roller sections encounter the said vibrator rollers. The sections of the vibrator rollers are slightly longer than the sections 46 of the ductor rollers, consequently the roller sections 46, along their entire length, 20 encounter the sections of the vibrator rollers, notwithstanding the fact that the said vibrator rollers reciprocate while they are in contact with the said ductor roller sections. The blocks 50 are arranged in stacks in the 25 slots 49 and engage each other at their ends, as shown in Fig. 3. Plates 58 are secured to the sides of the upper portion of the frame 30 and receive the end portions of the uppermost shaft 51 and thereby serve as means 30 for holding the blocks 50 in proper position in the slots 49. The peripheries of the vibrator rollers are spaced from each other as indicated by dotted lines in Fig. 3.

Guides 59 extend vertically along the 40 frame 30 and are disposed inwardly from the inner surfaces of the side thereof, (Fig. 19). Shafts 60 bear at their ends against the said guides 59 but are free to move vertically along the said guides. Roller sections 61 are mounted upon the shafts 60 and rest upon the sections of the vibrator rollers and correspond in number with the sections of the vibrator rollers and sections of the ductor rollers and fountain rollers. The 45 roller sections 61 upon the same shaft are spaced from each other and the said roller sections constitute what is hereinafter termed the distance rollers. The distance rollers correspond in number with the vibrator rollers, ductor rollers and fountain rollers. Consequently each distance roller section has its corresponding section in the other mentioned rollers.

Shafts 62 are journaled in the frame 30 50 and are provided with roller sections 63 spaced from each other upon the same shaft and which correspond in number with the sections of the distance rollers. The roller sections 63 upon the shafts 62 constitute 55 what is hereinafter referred to as the front

rollers and the front roller sections partially support the distance rollers inasmuch as the forward portions of the distance roller sections bear upon the peripheries of the front roller sections. Sprocket wheels 64 are 70 mounted upon the front roller shafts 62 in a vertical line and the said wheels are spaced from each other for a distance sufficient to permit the teeth of the adjacent wheels to escape each other. A shaft 65 is journaled 75 for rotation at one side of the frame 1 and carries a gear wheel 66 which meshes with the gear wheel 6 hereinafter described. The said shaft is also provided with a sprocket wheel 67 which is located at the 80 inner side of the frame 30. A sprocket wheel 68 is journaled for free rotation at the upper portion of the same side of the frame 30 adjacent which the sprocket wheel 67 is located and a sprocket chain 69 is trained 85 around the sprocket wheels 67 and 68. The links of the chain 69 at the forward flight thereof engage the teeth of the sprocket wheels 64 mounted upon the shafts 62 and consequently as the wheel 6 rotates the wheel 90 66 is rotated and through the shafts 65 and sprocket wheels 67 mounted thereon the chain 69 is moved longitudinally and rotary movement is transmitted to the front rollers which carry the sections 63. A shoe 70 is 95 adjustably mounted at the side of the frame 30 and bears against the inner surface of the forward flight of the chain 69, as best shown in Fig. 5 of the drawing, and serves as means for holding the forward flight of the chain 100 in engagement with the teeth of the sprocket wheels 64. Consequently when the press is in operation continuous rotary movement is applied to the shafts 62 and inasmuch as the roller sections 63 have contact with the distance roller sections 61 the said distance roller sections are rotated and this rotary movement is transmitted from the distance rollers to the vibrator roller 56 which in turn rotates the ductor rollers 46 when the 110 said ductor rollers are in contact with the vibrator rollers. The ink with which the ductor rollers 46 have been supplied, is transmitted to the vibrator roller sections 56, and from the said vibrator roller sections 115 61 and from thence to the front roller sections 63.

Shafts 71 (Fig. 2) are journaled for rotation in blocks 72, which are movably mounted upon the carriage 3 in the usual manner. 120 The shafts 71 are provided with inking or form roller sections 73 which correspond in number with the sections 63 of the front rollers. The inking roller sections 73 upon the same shaft are spaced from each other 125 and the form roller sections 73 on the adjacent shafts 71 are also spaced from each other as best shown in Fig. 2 of the drawing. Disks 74 are mounted upon the end portions of the shafts 71 and may be made of hide or 130

other suitable material. The disks 74 are in vertical alinement with relation to each other. Other disks 75 of similar character are also mounted upon the shafts 71 but the disks 75 are off-set or out of alinement vertically with relation to each other, as shown in Fig. 2. Upper follow tracks 76 are mounted upon the frame 30 and along which the disks 75 may move. The said upper follow tracks 10 76 have inclined ways, as best shown in Fig. 14 of the drawing, and when the disks 75 move down the inclination of the said ways the form roller sections 73 are brought into contact with the peripheries of the front 15 roller sections 63. Inasmuch as the said front roller sections 63 are supplied with ink and are maintained in a state of rotation this ink is transferred to the peripheries of the form roller sections 73. 20 Roller elevating cams 77 are mounted at the edges of the guides 2 at the upper edge of the chase 10 and the disks 74 are adapted to travel over these elevating cams and consequently the form roller sections 73 are 25 lifted over or clear the upper edge of the chase 10 as the shafts 71 move down along the chase. Roller elevating cams 78 are located at the lower portions of the guides 2 and the lowermost disks 74 may run along 30 the said cams 78 and lift the form roller sections 73 over the lower edge of the chase when the said roller sections override the lower edge of the chase.

Plates 79 are secured in any suitable manner in the side portions of the chase 10 and selecting cam track sections 80 are mounted upon the plates 79. Selecting cam track sections 80 are in alinement with the disks 75 of the corresponding set of form rollers and 35 40 the said disks 75 are adapted to move along the same. Each cam track shown in the drawing consists of two cam track sections the inner ends of which are spaced from each other as best shown in Figure 2 of the drawing. The sections of the cam tracks 80 are 45 adjustably mounted upon the plates 79 whereby the distance or space between the inner ends of the sections may be adjusted as desired. Blocks or forms 81 are secured 50 in the chase 10 and constitute the impression forms. The said blocks 81 correspond in number with the inking fountains and are arranged in similar transverse and longitudinal rows. Blocks 81 are so positioned with 55 relation to the spaces between the inner ends of cam tracks 80 that when the disks 75 enter the said spaces the peripheries of the form roller sections 73 come in contact with the faces of the blocks 81. That is to say the 60 parts are so arranged that each form roller section 73 comes in contact with its respective block 81 and therefore the ink which is carried by the said roller is transferred to the block and all of the blocks in a trans- 65 verse row or set are simultaneously supplied

with ink. After the blocks have been supplied with ink the carriage moves in an upward direction and the paper or sheet is placed upon the platen 8 and the platen moves toward the form and an impression 70 from the blocks is made upon the sheet.

Therefore it will be seen that ink of different colors and shades is transferred from the respective fountain containing each different color and shade to a certain block and 75 an impression upon a sheet of paper, or other material, is had from all of the blocks simultaneously whereby the different colors and shades are applied to the sheet.

For purposes of illustration a combination 80 of colors which may be obtained by the press on one impression of the platen is indicated on Fig. 2 and the corresponding arrangement of the colors of ink in the various fountains is shown in Fig. 15. It is to be understood however that the color arrangement shown is merely for the purpose of illustration and that any desired numbers, arrangements and combination of colors may be produced within the capacity of the press, 90 and that the capacity of a press may be varied by increasing or decreasing the active or actual number of fountains, forms and rollers.

Having described the invention what is 95 claimed is:—

1. A multi-color printing press having a plurality of sets of ink fountains each set containing a plurality of individual fountains, a plurality of sets of printing forms 100 corresponding to the number and arrangement of fountains, an ink distributing system individual to each set of fountains, and selecting means for selectively causing the transfer of ink from said systems to said 105 forms.

2. A multi-color printing press having a plurality of ink fountains arranged in multi-fountain sets, a plurality of printing forms corresponding in number and arrangement to the fountains, a set of form rollers for each set of fountains to transfer ink to the forms, selecting means to selectively bring sets of form rollers into engagement with corresponding sets of forms, 110 and sets of ink distributing rollers interposed between the fountains and form rollers, each set of distributing rollers transferring only the color of a corresponding set of fountains. 115

3. A multi-color printing press having a plurality of sets of stationary ink fountains, each set containing a plurality of individual fountains, a plurality of sets of printing forms corresponding in arrangement and 125 number to the fountains, sets of form rollers corresponding to the number of sets of fountains and acting to transfer ink to the forms, a set of individual ink distributing rollers interposed between each set of foun- 130

tains and a corresponding set of form rollers and acting to convey inks only between corresponding sets of fountains and form rollers, and selecting means for selectively operatively associating sets of form rollers with corresponding sets of forms and fountains.

4. A multi-color printing press having a plurality of individual printing forms arranged in sets, a plurality of stationary ink fountains arranged in corresponding sets, a set of ink conveying rollers for each set of fountains and conveying only the inks of a corresponding set, a form roller for each set of fountains, a reciprocating carriage for carrying the form rollers alternately into operative relation relative to the forms and the ink conveying rollers, and means for selectively causing the engagement of form rollers with corresponding sets of forms and ink conveying rollers.

5. A multi-color printing press having a plurality of sets of stationary vari-colored ink fountains, a plurality of individual forms arranged in corresponding sets, a set of ink conveying rollers for each set of fountains, each set of said rollers conveying only one color of ink circumferentially, a form roller for each set of fountains and carrying ink to the forms, and selecting means for selectively associating the form rollers, with corresponding sets of forms and ink conveying rollers.

6. A multi-color printing press having a plurality of sets of stationary vari-colored ink fountains, a plurality of individual forms arranged in corresponding sets, and a series of rollers individual to each set of fountains, and corresponding forms and selectively conveying ink from certain sets of fountains to corresponding sets of forms, no rollers of a set conveying inks of another set.

7. A multi-color printing press having a plurality of sets of stationary ink fountains, printing forms corresponding in number and sets to the fountains, a series of rollers for each set of fountains and carrying only the inks from the corresponding set of fountains, and means to selectively apply the inks from each series of rollers to corresponding sets of forms.

8. A multi-color printing press having a plurality of sets of ink fountains, a series of ink conveying rollers individual throughout to each set of fountains, a plurality of individual forms arranged in sets corresponding in number and arrangement to the fountains, a form roller for each set of fountains, and means for selectively bringing into ink transferring condition form rollers and corresponding sets of forms and ink conveying rollers.

9. A multi-color printing press having a plurality of sets of ink fountains each set containing a plurality of individual foun-

tains, a plurality of sets of printing forms corresponding in number and arrangement to the fountains, a form roller for each set of fountains and acting to apply ink to the corresponding set of forms, selecting means including cam tracks individual to each set of fountains and acting to cause the engagement of a form roller and its corresponding set of forms, and a set of intermediate rollers individual to each set of fountains and acting to convey inks from a set of fountains to a corresponding form roller.

10. A multi-color printing press having a plurality of individual printing forms arranged in sets, a plurality of individually adjustable ink fountains arranged in sets corresponding to the form sets, a series of intermediate ink conveying rollers individual to each set of fountains, a form roller individual to each set of fountains and adapted to receive inks from the corresponding series of intermediate rollers and apply the same to the corresponding sets of forms, means for causing the form rollers and forms to pass by each other, and selecting means for causing each form roller to apply ink to its corresponding set of forms and not to apply ink to the other sets of forms.

11. A multi-color printing press having a plurality of individual ink fountains arranged in sets of several fountains each, a fountain roller for each set of fountains, a reciprocating ductor frame for moving toward and from the fountain rollers, a plurality of ductor rollers carried by the ductor frame one for each fountain roller and contacting the same when the ductor frame is moved toward the fountain rollers, a plurality of form rollers one for each ductor roller, a series of rollers individual to and between each ductor roller, a series of rollers individual to and between each ductor roller and form roller to transfer the inks therebetween, a plurality of printing forms arranged in sets corresponding in number and arrangement to the fountains, means to cause relative movement between the forms and form rollers, and a series of selective cams for selectively causing contact between form rollers and corresponding sets of forms and preventing contact between the form rollers and other sets of forms.

12. A multi-color printing press having a type frame for holding a chase on which printing forms may be arranged in sets, a plurality of ink fountains which may be arranged in sets corresponding to the sets of forms, an individual series of ink distributing rollers for each set of fountains, and selecting means for causing a transfer of ink from each series of ink distributing rollers to a corresponding set of forms and preventing a transfer of ink between other series of rollers and sets of forms.

13. A multi-color printing press having a

type frame for holding a chase on which printing forms may be arranged in sets of several forms each, an ink fountain for each form and adjustable to form corresponding sets, a series of ink distributing rollers individual to each set of fountains and conveying only inks from a corresponding set to the forms, and selecting means including elements selectively set in the chase and actuating to selectively cause the transfer of ink from each series of ink distributing rollers to the corresponding set of forms.

14. A multi-color printing press having a plurality of ink fountains adjustable for arrangement in sets of several fountains each, a type frame for holding a chase on

which printing forms may be arranged in sets corresponding to the sets of fountains, cam tracks carried by the chase and arranged to correspond to the forms therein, a number of series of ink distributing rollers each series being individual to a set of fountains and corresponding forms, and means co-operating with the rollers and cam tracks for causing the selective inking of sets of forms by inks from the corresponding sets of fountains.

In testimony whereof we hereunto set our hands.

CHARLES A. RICHARDS.
MABEL M. RIESTER.
